UNITED STATES PATENT OFFICE.

WENCEL BROWN, OF MILWAUKEE, WISCONSIN, ASSIGNOR OF ONE-HALF
TO JAMES B. ERWIN, OF SAME PLACE.

SEWING-MACHINE SHUTTLE.

SPECIFICATION forming part of Letters Patent No. 278,303, dated May 22, 1883.

Application filed April 27, 1882. (No model.)

To all whom it may concern:

Be it known that I, WENCEL BROWN, a citizen of the United States, residing at Milwaukee, in the county of Milwaukee and State of Wisconsin, have invented certain new and useful Improvements in Sewing-Machine Shuttles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in sewing-machine shuttles, and pertains, first, to the device for regulating the tension of the thread as it is drawn from the shuttle; second, to the construction of the device by which the rear end of the tension-spring is attached to the heel of the shuttle-case.

The construction and operation of my improved shuttle are further explained by reference to the accompanying drawings, in which—

25 Figure 1 represents a perspective view of a shuttle embodying my improvements. Fig. 2 is an end view. Fig. 3 is a side view, and Fig. 4 is a longitudinal section.

Like parts are represented by the same reference-letters throughout the several views.

30 A is the shuttle-case. B is the bobbin. C represents the thread. D is the tension-spring. The spring D serves the twofold purpose of retaining the bobbin in the shuttle and producing the required tension of the thread. The front end of the spring D is attached to the case by an adjusting-screw, E, upon which the spring is free to be turned at an angle to the case when inserting and withdrawing the bob-

35 bin. The screw E is surrounded by a small spiral spring, a, which presses upward against the lower side of the tension-spring D, and retains said tension-spring against the head of said screw E, thereby preventing the tension-spring from vibrating loosely upward and downward on said screw, whereby the adjustment of the tension-spring may be made more positive and a more uniform tension attained.

40 d is a recess for the reception of the spring a. The rear end of the tension-spring D, is provided with a semicircular disk, b, which en-

gages in the rear end of the case and retains the bobbin therein, while it also retains the center of the spring D in close contact with the center of the case upon the thread, as shown, 55 whereby the tension of the thread is produced. The opening at the lower edge of the disk b, between the case and the edge of the disk b, is provided that the operator may insert his finger beneath the edge of the disk and thereby disengage the same from the end of the case, which object is accomplished by springing the lower edge of the disk outward slightly. The spring being thus disengaged, it is readily turned to one side, when the bobbin may be inserted or withdrawn. 60

I am aware that a circular disk has previously been attached to the tension-spring, which entirely closed the end of the shuttle-case, no provision being made for inserting a 70 person's finger between the edge of the disk and the shuttle-case, as shown by Patent No. 152,041.

It is obvious that in my device by forming the disk and tension-spring of the same piece 75 of elastic metal, the disk being semicircular in shape, and space being provided beneath the lower edge of said disk for the operator to insert his finger, he may, owing to the elasticity of the tension-spring, spring said disk outward, 80 and thus disengage it from the shuttle-case without mechanical appliances.

I am also aware that the end of a shuttle-case has been partially closed by a disk pivoted to the end of the case upon a horizontally-arranged pin, around which it is adapted to revolve in a vertical plane when opening said case, said disk having no connection with the tension-spring, the same being shown in Patent No. 220,816. 85

d' is an opening formed through the shuttle-case directly over the inner end of the bobbin, through which lint from the thread or other refuse matter may be observed and removed. The thread is drawn from the case through a short 95 opening, H, by which it is confined in its escape to the center of the shuttle-case beneath the center of the tension-spring, at which point it receives a uniform pressure from said spring, whereby a uniform tension is produced. The 100 thread is drawn into the opening H through the longitudinal slot I and transverse slot J.

It is obvious that as there is an open communication between the thread-passage H and the end of the case, the shuttle is thereby made, practically, self-threading, as the thread is drawn by the bobbin when being inserted in the case through slots I and J into the thread-passage H, and as the required tension is produced by the pressure of the spring D, but a moment is required for threading the shuttle and preparing it for work.

G is a bead or elevation formed around the opening H, over which the thread passes as it is drawn from the bobbin, and whereby it is retained in contact with and receives its tension from the central part only of the tension-spring. It is obvious that the elevation G supports the center of the tension-spring above the body of the case, leaving a space between the case and spring upon the respective sides of the elevation, through which the thread may pass freely without its tension being affected, while it is obvious that without such elevation the tension will necessarily be varied as the thread is drawn toward and from the center between the center and the respective ends of the tension-spring, the tension of said spring being uniform at a given point only. The front end of the spring D, when in its normal position, is retained at a slight distance from the case, and may be drawn downward by turning forward the screw E; or it may, by an inverse movement of the screw, be thrown upward by the action of the spiral spring a, whereby the center of the spring is caused to bear more heavily or lightly upon the thread, thereby increasing or diminishing the tension, as required.

Having thus described my invention, what I claim as new, and desire to secure by Letters Patent, is—

1. A shuttle-case provided with a longitudinal slot extending from its center to its heel, an opening or thread-passage at or near its center, and a transverse slot communicating from said central opening to said longitudinal slot, in combination with a tension-spring adjustably attached by a pivotal screw to the toe of the case, and adapted to be detachably connected to the heel of the case, the central part of said spring being adapted to bear upon the thread above said central opening, by which opening the thread is confined to the center of said spring, substantially as and for the purpose specified.

2. A shuttle-case for sewing-machines, having its central opening or thread-passage provided with an elevation or bead which surrounds said thread-passage, and forms a bearing over which the thread is drawn in contact with the tension-spring, and whereby the tension of the thread is confined to the center of said tension-spring, substantially as and for the purpose specified.

3. The shuttle-case A, provided with open slot I, transverse slot J, and thread-passage H, provided with the elevation G, in combination with the spring D, provided with semicircular disk b, substantially as set forth.

4. In a cylindrical shuttle-case, A, the opening d, formed above the inner end of the bobbin, adapted to facilitate the cleaning of the case, as set forth.

In testimony whereof I affix my signature in presence of two witnesses.

WENCEL BROWN.
